LINE BLIND

Leland S. Hamer, Long Beach, Calif., assignor of
one-fourth to Paul A. Dewhirst, Los Angeles,
Calif.

Application April 21, 1942, Serial No. 439,851

9 Claims. (Cl. 251—167)

This invention relates to pipe line equipment and relates more particularly to line blinds for blinding off or closing pipe lines, etc. A general object of this invention is to provide a simple practical and effective line blind in which the blind plate may be easily and quickly installed, removed or reversed.

Another object of this invention is to provide improvements of the general type of line blind disclosed in Patent No. 2,271,138 granted to me January 27, 1942.

Another object of this invention is to provide a line blind of the character referred to, embodying novel, readily retractible means for clamping the plate in position to close off the pipe, said means being retractible when loosened to allow the free introduction and removal of the plate. The two upper bolts, which serve to clamp the two body sections against the blind plate, may be easily retracted or spread apart to positions where they permit the free introduction and removal of the plate so that there is never any necessity for removing any of the bolts.

Another object of this invention is to provide a line blind of the character referred to in which the two upper bolts are automatically retracted upon withdrawing or inserting the blind plate as the case may be. The blind plate and the upper bolts are shaped and related so that movement of the plate to or from its position between the ends of the body sections automatically pushes or cams the loosened upper bolts to retracted positions where they allow free passage of the plate.

Another object of this invention is to provide a line blind of the character referred to embodying practical effective means for spreading the body sections to free the plate for removal or to condition the device for the ready insertion of the plate.

A further object of this invention is to provide a line blind of the character referred to which embodies only four nuts that require manipulation or use in the full operation of the line blind.

The various objects and features of my invention will be fully understood from the following detailed description of a typical preferred form and application of my invention, throughout which description reference is made to the accompanying drawing, in which:

Fig. 1 is a side elevation of the line blind provided by this invention. Fig. 2 is an end view of the line blind showing the bar nuts. Fig. 3 is an enlarged longitudinal detailed sectional view of the line blind showing the blind plate in position between the body sections. Fig. 4 is a slightly re-

duced transverse detailed sectional view taken substantially as indicated by line 4—4 on Fig. 3.

The improved line blind of the present invention may be said to comprise, generally, two body sections A and B having telescopically related engagement, a plate 10 arranged between the sections A and B, means 11 for urging the sections together to releasably clamp the plate 10 between the sections, and spreader means 12 for spreading the sections A and B to facilitate the introduction and removal of the plate.

The two body sections A and B constitute an assembly adapted to be installed or connected between the opposing adjacent ends of pipes P or other fluid handling parts. The sections A and B are simple members, preferably constructed to be easily and quickly secured to the adjacent ends of the pipes P. In practice the sections A and B may be constructed to be welded, bolted or screw threaded on the pipes. In the particular construction illustrated in the drawing the sections A and B are designed to be screw threaded on the pipes, each section having a central threaded opening or socket 13 for receiving the threaded end of its respective pipe P. The body sections A and B are complementary similar members resembling flanges.

The outer side of the section A has a boss or hub 14 in which the threaded opening 13 is formed and the inner side of the section A has a hub 15 of larger diameter. The inner hub 15 has a central longitudinal socket or opening 16 of larger diameter than the fluid openings 11 of the sections A and B. The bottom or inner wall 18 of the opening 16 forms an annular shoulder which lies in a plane transverse of the longitudinal axis of the device. A transverse or lateral opening or slot 19 is formed in the hub 15 and joins the opening 16. The lateral opening or slot 19 is provided to receive the plate 10. The width or transverse dimension of the opening 19 is at least equal to the diameter of the opening 16 and the edge walls of the slot 19 may extend tangentially outwardly or upwardly from the wall of the opening 16. The opening 19 is open at the top of the hub 15 to receive the plate 10. The lateral opening 19 occurs at the inner end of the hub 15 so that the above described wall 18 is co-extensive with the inner side wall of the lateral opening 19. A drain opening 20 is provided in the lower wall of the hub 15 and is normally closed by a threaded-in plug 21. The drain opening 20 provides for the draining of the fitting and the pipe line when the plate 10 is installed, replaced or reversed.

The section B of the fitting may have a plain flat outer side or end. A boss or hub 22 is formed on the inner side of the section B and projects into the opening 16 of the hub 15. In practice the hub 22 fits the opening 16 with considerable clearance. The threaded socket 13 for the pipe P extends through the body of the section B and enters the hub 22, the opening 17 of the section B continuing inwardly to the inner end of the hub. The inner end of the hub 22 constitutes a flat annular surface 23 which is spaced from and parallel with the wall 18. The wall 18 and the surface 23 are adapted to clamp against opposite sides of the plate 10, as will be hereinafter described.

The invention preferably includes means for slidably sealing between the sections A and B to prevent the drainage or leakage of fluid from between the sections when the plate 10 is being installed, replaced or reversed. An annular body or ring 24 of packing is set in a groove in a wall of the opening 16. The sealing ring 24 is spaced outwardly or away from the lateral opening 19 and the sealing ring projects inwardly from the wall of the opening 16 to seal with the periphery of the hub 22. Where petroleum products are to be handled by the device, the sealing ring 24 may be formed of a synthetic rubber which will expand through contact with the fluid to maintain an effective seal between the two body sections A and B.

The plate 10 is adapted to be engaged or clamped between the sections A and B to blind off or close off the pipe line. The plate 10 may comprise two joined or connected portions 25 and 26. The two plate portions 25 and 26 are generally disc-shaped and the portion 25 is closed or imperforate while the portion 26 has an orifice or opening 27. When the device is employed as a line blind the opening 27 is preferably of the same diameter as the opening 17 so that when the portion 26 is engaged between the sections A and B there is a free unrestricted fluid passage through the device. When the device or fitting is to be used as an orifice meter fitting the orifice 27 may be considerably smaller than the openings 17 so that the plate portion 26 may operate as an orifice plate. The plate portions 25 and 26 are proportioned so that they may be readily passed into the lateral opening 19 to occupy a position between the wall 18 and the surface 23. The radius of curvature of the peripheries of the portions 25 and 26 may be equal to or slightly less than the radius of the opening 16 so that the plate portions are effectively guided into position by the side or edge walls of the transverse opening 19 and so that the peripheral edges of the plate portions may bear on the bottom or inner wall of the opening 16 to centralize or locate the plate portions.

It is preferred to provide means for sealing between the opposite faces of the plate 10 and the wall 18 and surface 23 of the sections A and B. In the case illustrated suitable gaskets 28 are provided on the opposite sides of the plate portion 25 to seal with the wall 18 and surface 23. It is to be understood that appropriate sealing means may be provided on the wall 18 and the surface 23 to seal with the opposing surfaces of the plate 10.

The means 11 serves to connect the body sections A and B and is operable to clamp the sections against the plate 10 to retain the plate in the lateral opening 19 and to assure tight seals between the plate and the sections. In accord-

ance with the invention the means 11 comprises a limited number of spaced aligned or complementary lugs on the flange sections A and B. The lugs occur on the peripheries of the flange-like sections A and B and are preferably integral parts of the sections. In the preferred construction illustrated there are four substantially equally spaced lugs on each section A and B, namely, two lower lugs 30 and two upper lugs 31. The lower lugs 30 may be partially disc-shaped, while the upper lugs 31 are in the nature of upper corner portions of the flange sections A and B, which corner portions may be generally angular. The lower lugs 30 have aligned axial openings 32 for receiving studs or bolts 33. In accordance with the invention the openings 32 are flat walled or polygonal and the bodies of the bolts 33 are correspondingly shaped to fit the openings. For example, the openings 32 may be hexagonal and the bodies of the bolts 33 may be hexagonal. The fit or engagement of the bolts 33 in the openings 32 positively holds the bolts 33 against rotation. The opposite end portions of the bolts 33 are cylindrical and screw-threaded, and project beyond the outer faces of the flange sections A and B.

The section connecting and plate clamping means 11 further includes slots 34 in the upper lugs 31. The slots 34 are horizontal, that is, their long axes are normal to the longitudinal axis of the lateral opening 19. The slots 34 have flat parallel upper and lower walls of substantial extent and the end walls of the slots 34 may each be defined by two converging walls 35. Studs or bolts 36 are passed through the aligned or complementary slots 34 of the two body sections A and B. The bolts 36 are flat sided and have flat surfaces which cooperate with the longitudinal walls of the slots 34, this engagement serving to positively hold the bolts against rotation. In practice the bolts 36 may be the same as the bolts 33, that is, the bodies of the bolts 36 may be hexagonal. The upper and lower surfaces of the hexagonal bolt bodies slidably ride on the upper and lower walls of the elongate slots 34.

The hexagonal bolts 36 engaged in the slots 34, as just described, each has a flat face 37 sloping downwardly and inwardly toward the longitudinal axis of the device and a flat face 38 sloping downwardly and outwardly. The faces 37 on the sides of the two opposing bolts 36 may be engaged by the periphery of a plate portion 25 or 26 when the same is being inserted in the opening 19 and this engagement may result in outward movement or spreading of the two bolts 36. The downwardly and outwardly pitched faces 38 of the bolts 36 may be engaged by the periphery of the plate portion 25 or 26 when the latter is being withdrawn from the fitting and this engagement may cam apart or spread the bolts 36. With the bolts loose or free the engagement of the plate 10 with the surfaces 37 or 38, as the case may be, effectively serves to automatically spread the bolts 36 to positions where they permit the free entry or withdrawal of the plate 10. The slots 36 are sufficiently long to allow the bolts 36 to be moved to outer positions where they permit the free movement of the plate 10 into or out of the lateral opening 19. In this connection it should be observed that the angularly related outer side faces of the bolts 36 may cooperate with the convergent walls 35 of the slots 34 and that the walls 35 provide for maximum outward movement of the studs. With

a plate portion 23 or 26 in the operative position the bolts 36 may be shifted inwardly to the inner end portions of the slots 34.

The means 11 further includes nuts threaded on the studs or bolts 33 and 36. There may be a nut threaded on each end of each bolt 33 and 36. The nuts may be of typical or conventional character but it is preferred to provide what I will term a "bar nut" 39 on one end of each bolt 33 and 36. The bar nuts 39 each have two or more circumferentially spaced ears 39a, and these ears 39a have lateral or tangential openings 40 for receiving a turning bar or rod. In the case illustrated there are three ears 39a on each nut 39. With the nuts 39 constructed in this manner a lever turning bar may be readily inserted in one of the openings 40 with a nut in any rotative position. In the construction illustrated there is a bar nut 39 on one end of each bolt 33 and 36. The bar nuts 39 are shown on corresponding ends of the several bolts to cooperate with the plain outer side of the section B. Common or conventional nuts 41 may be threaded on the other ends of the bolts 33 and 36 to cooperate with the outer face of the section A. The nuts 41 may be threaded inwardly to selected positions with their inner faces in a common plane to engage the section A and may be left in these positions indefinitely because it is unnecessary and, in fact, impossible to turn the bolts 33 and 36 when operating the device. It will be apparent how rotation of the nuts 39 in the correct direction will cause the sections A and B to be urged together to tightly clamp the plate 10 between the sections.

The invention may further include means 12 for spreading the sections A and B to facilitate the free removal, reversal and insertion of the plate 10. There are preferably two diametrically opposite spreading means 12. In the case illustrated the spreading means 12 are located at the opposite sides of the line blind. Each means 12 includes a spreader screw 42 threaded through an opening 43 in the flange portion of the section B. The inner end of each screw 42 reacts or bears against a lug or boss 44 on the inner side of the section A. The portion of the screw 42 between the sections A and B is preferably polygonal for engagement by a wrench. It will be seen that by rotating the screw 42 in the correct direction the screw presses against the boss 44 to spread or exert a spreading force on the sections A and B. With the nuts 39 loosened the spreader screws 42 may be employed to shift the sections A and B away from one another to free the plate 10 for ready removal or to facilitate the easy insertion of the plate.

It is believed that the utility and practicability of the line blind provided by this invention will be readily understood from the foregoing detailed description. With the plate portion 25 disposed in the position illustrated in Fig. 3 of the drawing, and with the nuts 39 tightened against the section B the plate is securely held between the two sections and the pipe line is completely closed off. The gaskets 28 tightly compressed between the surfaces of the plate 10 and the opposing wall 15 and surface 23 assure fluid tight seals at opposite sides of the plate. When it is desired to remove the plate 10 or to reverse the plate to permit a free flow of fluid through the pipe line the bar nuts 39 are backed off. This is readily accomplished by merely inserting the end portion of a bar in the openings 40 and exerting a turning force on the nuts. It is not necessary to re-

move the nuts 39 and the nuts may be merely loosened or backed off. When this has been done the spreading screws 42 may be rotated to press against the bosses 44 to spread the sections A and B. This spreading of the sections A and B fully frees the plate 10 and the plate may be readily withdrawn from the lateral opening 18. In the event the upper studs or bolts 36 have not been retracted or spread outwardly in their slots 34 the upward withdrawal of the plate portion 25 from the opening 18 results in the automatic retraction of the studs. The periphery of the plate portion 25 cooperates with the bolt surfaces 38 to move the bolts outwardly to their retracted positions so that the plate portion 25 may be freely removed. With the plate 10 withdrawn from the line blind the packing 24 prevents fluid from draining or leaking from the line and thus eliminates dangerous fire hazards where inflammable fluids are handled.

When the plate 10 is to be replaced, for example, when the plate portion 26 is to be clamped between the sections A and B, the portion 26 is merely passed inwardly through the opening 18 to its position between the wall 18 and the surface 23. The plate portion 26 may be equipped with gaskets similar to the gaskets 28. The bolts 36 are in their retracted positions at the outer ends of the slots 34 and the plate portion 26 is free to pass in through the opening 18. With the plate portion 26 engaged against the bottom wall of the opening 18 the bolts 36 are restored to their active positions at the inner ends of the slots 34 and the bar nuts 39 of the several bolts 33 and 36 are tightened against the section B. Prior to this the spreader screws 42 are retracted from the bosses 44 so that the clamping of the nuts 39 against the section B forces the sections A and B toward one another. This results in the wall 18 and the surface 23 tightly clamping against the plate portion 26 to secure the same in place and to assure fluid-tight seals.

It is to be observed that it is unnecessary to remove any nuts or bolts when installing, reversing or replacing the blind plate. The lower bolts 33 may always remain in position while the upper bolts 36 are either manually shifted between their active and retracted positions or automatically retracted upon insertion or removal of the plate and, in no case, is it necessary to withdraw any of the bolts. The line blind is fully operable by a minimum number of simple tools. A simple bar or rod is all that is required to loosen and retract the bar nuts 39 and a simple wrench is all that is necessary to operate the spreader screws 42.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A fitting of the character described comprising two flange sections having a fluid passage and having means for connecting with fluid conductors, telescopically related hubs on the inner sides of the sections, the outer hub having a lateral opening and an internal seat, a plate to be inserted in the opening to extend across the passage, and means for urging the sections toward one another so that the plate is clamped between the seat and the inner end of the inner hub, said means including clamp bolts circumferentially

spaced around the assembly of sections, one or more of the bolts extending across the mouth of said opening preventing movement of the plate through the opening, the sections having openings for passing the bolts, those openings which pass said bolts which extend across the mouth of said lateral opening being in the form of slots the outer ends of which are beyond the path of the plate as it passes through the opening so that the bolts may be shifted in the slots to retracted positions at the outer ends of the slots where they do not interfere with the insertion or removal of the plate, and nuts screwed on the bolts.

2. A fitting of the character described comprising two flange sections having a fluid passage and having means for connecting with fluid conductors, telescopically related hubs on the inner sides of the sections, the outer hub having a lateral opening, a plate to be inserted in the opening to extend across the passage, and means for urging the sections toward one another so that the plate is clamped between the seat and the inner end of the inner hub, said means including clamp bolts circumferentially spaced around the assembly of sections and having polygonal intermediate portions, one or more of the bolts extending across the mouth of said opening, the sections having spaced polygonal openings receiving the polygonal portions of the bolts, the engagement of the polygonal bolts in the polygonal openings holding the bolts against rotation, and nuts threaded on the bolts to cooperate with the sections, those bolt-passing openings which receive the bolts which extend across the mouth of the lateral opening being in the nature of slots whose longitudinal axes are substantially normal with respect to the axis of movement of the plate into and out of said lateral opening the outer ends of which are beyond the path of the plate as it passes through the opening so that the bolts therein may be shifted to retracted positions in the slots where they do not interfere with the insertion or removal of the plate but are held against rotation.

3. A fitting of the character described comprising two flange sections having a fluid passage and having means for connecting with fluid conductors, telescopically related hubs on the inner sides of the sections, the outer hub having a lateral opening, a plate to be operated into and out of the opening to extend across the passage, and means for urging the sections toward one another so that the plate is clamped between the seat and the inner end of the inner hub, said means including clamp bolts extending across the mouth of said lateral opening and having polygonal intermediate portions, the sections having slots receiving said portions of the bolts, the long axes of the slots being transverse of the movement of the plate when the plate is inserted and removed so that the bolts may be shifted from their normal positions across the mouth of the opening to retracted positions removed from the mouth of the opening where they do not interfere with the insertion or removal of the plate, the engagement of said polygonal portions in the slots preventing rotation of the bolts, and nuts screwed on the bolts to cooperate with the sections, said polygonal portions of the bolts presenting surfaces engageable by the plate, upon operation of the plate, to cam the bolts to said retracted positions.

4. A fitting of the character described to be connected between fluid conductors comprising two flange sections having fluid passages, a plate insertable between the sections, and means for

clamping the sections against the plate comprising clamp bolts, the sections having slots for receiving the bolts so they are movable into and out of positions where they are in the path of movement of the plate as it passes from between the sections, nuts on the bolts, and means for spreading the sections when the nuts are loosened.

5. A fitting of the character described to be connected between fluid conductors comprising two flange sections having fluid passages, a plate insertable between the sections, and means for clamping the sections against the plate comprising clamp bolts, the sections having aligned slots for receiving the bolts, nuts on the bolts, the bolts being movable in the slots from opposite the plate to retracted positions to allow for the insertion of the plate between the sections, one section having spaced threaded openings, and spreading screws threaded in the last named openings and reacting against the other section.

6. A fitting of the character described to be connected between fluid conductors comprising two flange sections having fluid passages, a plate adapted to be passed into and out of position between the sections, and means for clamping the sections against the plate and obstructing the passage of the plate including a bolt extending through registering slots in the flange sections and a unit on the bolt for tightening the sections together, the said slots being formed to slidably carry the bolt when the nut is released and extending from a point in the path traveled by the plate in passing to or from position between the sections to a point out of the said path of the plate.

7. A fitting of the character described to be connected between fluid conductors comprising two flange sections having fluid passages, a plate adapted to be passed into and out of position between the sections, and means for clamping the sections against the plate and obstructing the passage of the plate including a bolt extending through registering slots in the flange sections and a nut on the bolt for tightening the sections together, the said bolt having a flat sided intermediate portion and the said slots slidably carrying said portion of the bolt to prevent it from turning when the nut is operated, the slots extending in a direction transverse of the longitudinal axis of the fitting from a point in the path traveled by the plate in passing to or from position between the sections to a point out of the said path of the plate.

8. A fitting of the character described to be connected between fluid conductors comprising two flange sections having fluid passages, a plate adapted to be passed into and out of position between the sections, and means for clamping the sections against the plate and obstructing the passage of the plate including spaced bolts extending through registering openings in the flange sections and each having an intermediate portion polygonal in cross section, nuts on the bolts for tightening the bolts on the flange sections, the flange sections having slots slidably carrying the said portions of the bolts between positions where the bolts are clear of the path of the plate as it passes into or out of position between the sections and positions where they are in the path of the plate as it passes into or out of position between the sections and present convergent faces engageable by the plate as it is moved in said path so the bolts are moved by means of the plate to the first mentioned positions.

9. A fitting of the character described comprising two flange sections having a fluid passage and having means for connecting with fluid conductors, telescopically related hubs on the inner sides of the sections, the outer hub having a lateral opening, a plate to be inserted in the opening to extend across the passage, and means for urging the sections toward one another so that the plate is clamped between the seat and the inner end of the inner hub, said means including clamp bolts extending between the sections opposite the mouth of said lateral opening and having polygonal intermediate portions, the sections having slots receiving said portions of the bolts, the long axes of the slots being lateral of said opening and 10 15

transverse of the direction of movement of the plate when the plate is inserted and removed so that the bolts may be shifted from their normal positions opposite the mouth of the opening to 5 retracted positions where they are removed from the path of the plate as it is operated through the mouth of the opening, the engagement of said polygonal portions in the slots preventing rotation of the bolts, nuts screwed on the bolts to cooperate with the sections, and means for spreading the sections when the nuts are loosened comprising a threaded screw on one section for pressing against the other section.

LELAND S. HAMER.
